UNITED STATES PATENT OFFICE

WILLIAM R. SMITH, OF CHICAGO, ILLINOIS

WATER HEATING ATTACHMENT FOR BOILERS

Application filed June 30, 1931. Serial No. 547,924.

My invention relates to a water heating attachment or equipment for installation particularly in steam boiler structures for the heating of water in a water supply system before reaching the points of consumption.

An important object of the invention is to provide a water heating loop for installation in a boiler structure in which water flowing therethrough is heated partially by the hot water or steam in the boiler and partially directly by the heat or products of combustion in the fire box for the boiler structure.

A further object is to provide an arrangement in which two of the boiler tubes, or tubes substituted therefor are included in the water heating loop for exposure to the heat of the water or steam in the boiler, and a header connecting the front ends of these tubes and extending through the fire box for direct exposure to the fire and heat is also included.

A still further object is to provide a water heating loop whose side sections extend through the boiler to be supported by the tube sheets of the boiler and whose front ends are connected by a head of extended volume and heating surface for exposure directly to the fire in the fire box so that water flowing through the loop is partially heated directly by the fire and partially by the water in the boiler, with the loop delivering heat to the boiler when the temperature of the water therein is higher than the temperature of the boiler water.

A further object is to provide a structure which can be easily and readily installed, which comprises simple and inexpensive parts, and which will rapidly and efficiently heat and maintain the water at the required temperature for distribution through the hot water supply system.

The above and other features of the invention will be apparent from the structure and arrangement disclosed on the drawing, in which

Figure 1 is a side elevation, partly in vertical longitudinal section, of a boiler structure and my water heating attachment applied thereto;

Figure 2 is a section of the boiler housing

on plane II-II of Figure 1, with the boiler partly in section and the water heating loop in plan elevation; and

Figure 3 shows a flue in longitudinal section and one leg of a water loop therein.

The boiler structure shown is of the well-known "Kewanee" type comprising the horizontal tubular boiler body 10 between whose front and rear tube sheets 11 and 12 extend the flues 13. The boiler is set on brick structure 14 and at the front thereof is the fire or combustion box 15 over the grate structure 16. Above the flues the wall 17 extends forwardly from the front crown sheet 11 to form the upper wall of the fire box 18 and connects with the front wall 18 of the fire box into which fuel is fed through the doorway 19. The upper space 20 of the boiler above the flues extends forwardly to communicate with the water jacket or legs 21 surrounding the fire box.

The water heating loop comprises a head structure 22, side conductors 23 and 24 and the leads 25 and 26 for connecting the loop serially in the water supply system usually extending from a water main to the different points of hot water consumption. My improved arrangement is such that the side members or conductors 23 and 24 extend through the boiler for exposure to the water therein while the head 22 is within the fire box for direct exposure to the fire and heat therein. I may use two of the boiler flues for inclusion in the water heating loop but preferably I substitute other tubes for such flues with the tubes extending sufficiently beyond the outer sides of the boiler tube sheets for application thereto of suitable fittings for securing thereto the head 22 and the leads 25 and 26. The location of the tubes 23 and 24 may be at desired points in the boiler but a preferred construction is to utilize the spaces ordinarily occupied by the upper and side flues for the boiler. When a boiler is manufactured for use therein of my water heating attachment, the pipes 22 and 24 are inserted and secured to the crown sheets in the ordinary manner, as for example, by welding or brazing. When the loop is to be installed in a boiler structure

which is already in use, two of the flues are removed and the loop pipes 23 and 24 substituted therefor and secured in place. The outer ends of the pipes are preferably 5 threaded for receiving suitable joint or coupling members. I have shown a head 22 of substantially U-shape whose ends 27 and 28 are secured to the ends of the pipes 23 and 24 by coupling or joint members 29 and 30, 10 and the distributing leads 25 and 26 are connected with the other ends of the pipes by coupling or joint members 31 and 32.

Where the pipes 23 and 24 are located in the upper and side flue holes, the head structure 15 22 will project into the fire box near the top thereof and the shape and extent of the head will depend upon the degree and rapidity of heating desired or upon the proportionate direct fire heating of the water to 20 the heating of the water in the loop by the water or steam in the boiler. I have shown the head 22 laterally expanded so as to spread the water flowing therethrough along the extended area of the header which will be exposed to the flame and heat in the fire box. The header may be in the form of a casting or may be constructed of suitable sheet metal parts welded or otherwise secured together. Instead of the special shaped header, a length of pipe or a coil of piping could 25 be extended between the ends of the tubes 23 and 24 for direct exposure to the heat in the fire box.

Where the flues of a boiler are of comparatively large diameter, flues need not be removed for the installation of the hot water loop, but as shown in Figure 3 the side legs 33 of the loop could be extended through the desired flues. The pipes could also be of a 30 length so that the joints or connection thereof with the leads 25 and 26 would be outside of the furnace or boiler structure walls. The side pipes for the loops could then be inserted from the rear end of the boiler structure 35 through the desired flues and the header 22 and the leads then connected with the respective ends of the pipes.

I thus provide a water heating attachment or loop structure comprising a minimum 40 number of simple, inexpensive parts easily and readily assembled and installed in connection with the boiler for the heating of the water flowing therethrough partly by the direct heat of the fire box and partly by the water or steam in the boiler. Where the 45 header 22 is of extended exposure surface for rapid heating directly by the fire, the heated water in the loop may assist in heating the boiler water during periods when hot 50 water is not being drawn in great quantities from the hot water supply circuit. At other times the extended header 22 will maintain the water at the proper temperature for maximum supply of hot water to the hot water 55 circuit.

By utilizing the upper flues or flue passages for application of the water heating loop, the header 22 will be near the top of the fire box so that it will not interfere with proper firing or combustion conditions. 70

I have shown a practical and efficient embodiment of the features of my invention, but I do not desire to be limited to the exact construction and arrangement disclosed and described as changes and modifications may 75 be made without departing from the scope and spirit of the invention as defined in the appended claims.

I claim as follows:

1. The combination with a boiler and a fire box for supplying heat therefor, of a water heating loop adapted for inclusion in a hot water supply circuit, said loop comprising pipes extending through the boiler for heating of the water therein by the boiler water and a header connecting the ends of the pipes and located entirely within the fire box and extending horizontally thereacross adjacent the top of the fire box, for direct heating of the water by the fire. 80

2. The combination with a boiler and a fire box therefor of a water heating loop comprising pipes extending through the boiler and the tube sheets thereof, a header structure connected with the front ends of the pipes to be disposed entirely within the fire box and extending horizontally thereacross adjacent the top of the fire box for direct heating of the water therein by the fire, the rear ends of said pipes being adapted to connect the loop in a hot water supply system. 85

3. The combination with a boiler having flues extending therethrough and a fire box communicating with said flues at the front ends thereof, two of said flues forming the sides of a water heating loop, a header connecting the front ends of said two flues to complete the loop, said header being entirely within the fire box for direct heating by the fire and said two flues being heated by the boiler water, said header comprising a relatively large flat hollow fluid container extending horizontally across the fire box adjacent the top thereof, the rear ends of said two flues being adapted for connection with a hot water supply line for inclusion of the loop therein. 90

4. The combination with a boiler and a fire box therefor, of a water heating U loop having its legs extending through the boiler and its bend entirely within the fire box and extending horizontally thereacross adjacent the top of the firebox whereby water flowing through the loop will be partly directly heated by the fire and partly by the water of the boiler, the loop at its ends being adapted for connection for inclusion in a hot water supply system. 95

5. The combination with a boiler having flues therethrough and a firebox communi- 100

cating with the flues, the upper side flues forming side legs of a water heating loop, a connection between the front ends of said two flues completing the loop and being disposed entirely in the fire box and extending horizontally thereacross adjacent the top of the firebox, and exposed to direct heating by the fire, the rear ends of said two flues being adapted for connection with a water supply circuit to include said loops therein.

6. The combination with a boiler having flues and a fire box communicating therewith, of a water heating coil comprising pipes extending through some of said boiler flues, a header connecting the front ends of said pipes and located entirely within the firebox to be exposed to the direct heat of the fire, said header comprising a relatively large flat hollow fluid container extending horizontally across the fire box adjacent the top thereof, the rear ends of said pipes being adapted for connection with a hot water supply circuit for inclusion of said coil therein.

In testimony whereof I have hereunto subscribed my name at Chicago, Cook County, Illinois.

WILLIAM R. SMITH.
